SEALING SHEET APPLYING APPARATUS

Edgar Ardell, Middletown, Conn., assignor to
Hartford-Empire Company, Portland, Conn., a
corporation of Delaware

Application May 24, 1949, Serial No. 95,003

10 Claims. (Cl. 216—30)

1

This invention relates to a machine for applying stickers or sheets of paper, fabric, or the like, to articles. Although the machine can be used wherever it is desirable to apply such sheets to articles having a sufficiently flat surface to receive them, the invention will be described as embodied in a machine for closing the spouts of containers for salt or like dry granular or pourable products and applying a sealing sheet thereover.

Such products are customarily packaged in cylindrical containers or cans, usually formed of cardboard and provided with pouring spouts hingedly secured to the top of the container and movable in an opening in the top from open to closed positions. In one well known construction, the spout forms a closure which substantially closes the opening in the container top when the spout is moved to its closed position. In the packing of such materials, the containers are filled with the spouts open and it is necessary thereafter to close the spouts and to seal them against accidental opening and leakage. This sealing is preferably accomplished by adhesively securing a small sheet of thin paper over the closed spout and the adjacent portions of the container top which surround the spout and the opening through which it moves.

In the copending application of Fischer and Ardell, Serial No. 605,540, filed July 17, 1945, and assigned to the same assignee as the present application, now Patent 2,483,458, there is disclosed and claimed an apparatus of this general type. This prior apparatus has proved to be successful in commercial operation, particularly in closing the spouts of salt containers and applying sealing sheets adhesively secured as above described and employing a liquid, paste or gum type of adhesive.

The general object of the present invention is to improve the construction of the prior apparatus, and especially to provide a machine of this sort which is capable of applying sheets coated with a thermoplastic adhesive, that is to say, an adhesive which is dry at ordinary room temperatures but which is conditioned, that is, rendered tacky or sticky by the application of heat. The thermoplastic adhesive coated sheet is applied to the container while its adhesive coating is heated or conditioned, and upon cooling the adhesive returns to its hard or dry condition and serves adhesively to secure the sheet to the surface of the container.

Another object of the present invention is to increase the speed of operation so as to seal the

2

containers at a higher rate than in the previous apparatus.

Another object of the invention is to provide a machine in which the parts thereof which feed and apply the individual sheets to the containers operate with continuous, instead of intermittent, motion.

Another object of the invention is to provide for the cutting of a continuous strip or web of paper, or the like, into individual sealing sheets in such a way as to prevent the heat from the applying mechanism from interfering with the operation of the severing mechanism.

The invention will be understood upon a consideration of the accompanying drawings illustrating its embodiment, by way of example, in a spout closing machine as above referred to. In these drawings:

Fig. 1 is a view of the spout closing machine in side elevation;

Fig. 2 is a plan view;

Fig. 3 is a vertical section taken on line 3—3 of Fig. 1 looking toward the left, some parts being omitted;

Fig. 4 is a vertical section taken on line 4—4 of Fig. 7, also looking toward the left;

Fig. 5 is a horizontal section taken on line 5—5 of Fig. 1;

Fig. 6 is a plan view of a detail;

Fig. 7 is an enlarged elevation of the web cutting and sheet carrier mechanism, with parts shown in vertical section;

Fig. 8 is a vertical section showing some of the parts of Fig. 7 in a different position, the section being taken on line 8—8 of Fig. 5;

Fig. 9 is an enlarged elevation of the rotary head which applies the sheets to the containers;

Fig. 10 shows the outline of a slotted cam also shown in Fig. 9;

Fig. 11 is a transverse vertical section taken on line 11—11 of Fig. 9;

Fig. 12 is a horizontal section taken on line 12—12 of Fig. 8; and

Fig. 13 is a vertical section of a detail taken on line 13—13 of Fig. 11, looking toward the right.

Referring now to these drawings, the containers C₁, C₂, C₃ and C₄ are advanced in the direction of the arrow shown in Fig. 2 on a rotating table 1 of a filling machine where the salt or other granular material is poured into the containers. As they reach the position C₁, the containers are removed from table 1 by means of a succession of flight members 2 which are mounted in spaced relation on a flight chain 3. This flight chain

travels in a horizontal plane and carries the containers toward the left along a horizontal table 4. After the spouts are closed and sealed the containers move onto a rotating turntable 5 which delivers them in any desired direction to the next operation, such, for example, as a packing machine. Guides 6 keep the containers in a straight path on table 4 and direct them across the turntable.

As the succession of containers travels over table 4 their respective pivoted spouts 7 are first rotated to closed position by means of a cam device 8 and thereafter the containers each receive a sealing sheet S_4 over the closed spout from a continuously rotating head, indicated generally by numeral 9. The sealing sheets are cut from a continuous web 10 of paper which is fed from a magazine roll 11 by means of a feed roll 12 to a cutting mechanism, indicated generally by numeral 13. This delivers the cut sheets to a rotary carrier 14 by which they are transferred from the cutting mechanism to the rotary head 9 which applies them to the containers. Reference numerals S_1 , S_2 , S_3 and S_4 indicate four sealing sheets at various positions in their movement.

The foregoing describes the general arrangement and operation of the apparatus, whose construction will now be considered more in detail. The principal frame of the apparatus consists of a member 15, preferably in the form of an iron casting. Power for driving the apparatus is applied through a vertical shaft 16 (Fig. 3) which, through beveled gearing 17, drives a short horizontal shaft 18. Flight chain 3 is driven by means of a sprocket 19 on the vertical shaft 16. This chain is trained around sprockets 20 and 21, at the right and left sides of the machine respectively. Sprocket 21 is keyed to its shaft, and fixed to the lower end of the shaft is a sprocket 21a which, through chain 21b, drives the turntable 5. Rotary head 9, rotary carrier 14, severing mechanism 13 and feed roll 12 are all driven from short shaft 18 through suitable gearing and sprocket chain, all of which will be described presently.

Rotary head 9 (Figs. 3, 9 and 11) comprises a body member 22, four sheet carrying and applying devices, indicated generally by numeral 23, and a stationary control cam member 24. Body member 22 is secured by means of a key 25 to the front end of a horizontal shaft 26 which is supported in bearings in frame 15 and rotated by means of a large gear 27 which meshes with a pinion 28 on short shaft 18. Body member 22 is provided with four enlargements 29 which project in a radial direction and also towards the front of the machine from the central portion of member 22 which is of generally circular form. Each of the enlargements 29 has four holes drilled in its face within which four tubes 30 (Figs. 9 and 3) are fixed. The outer ends of each of these groups of four tubes constitute a supporting surface for a sealing sheet such, for example, as shown at S_1 , S_2 , S_3 and S_4 (Fig. 1).

The sealing sheets are held on the ends of tubes 30 by suction, and for this purpose the inner ends of tubes 30 communicate with horizontal drilled passages 31 (Fig. 11) which extend to the rear vertical surface of body member 22 and communicate with a vacuum groove 32 which is connected through a pipe 33 to an appropriate vacuum source. Vacuum groove 32 extends in the clockwise direction, which is the direction of rota-

tion of rotary head 9, for about two-thirds of a complete revolution of the head and terminates just before the sheet carrying devices 23 reach their lowermost position, which is the point where the sealing sheets are applied to the cans.

5

As carrying devices 23 continue their movement the passages 31 rotate into communication with a short second groove 34 to which air pressure is supplied through a tube 35 (Figs. 5 and 9).

10

Vacuum groove 32 and pressure groove 34 are formed in a stationary annular member 36 which is urged by means of coil springs 37 toward the left as shown in Fig. 11 so as to maintain it in contact with the surface of body member 22 of the rotary head. Springs 37 are mounted upon pins 38 fixed in frame 15 and serving to support member 36 which is provided with suitable apertures arranged to fit slidably on the outer end portions of these pins. The engaging flat surfaces of member 36 and body 22 are suitably finished to provide the necessary fluid-tight joint therebetween. The drilled passages 31 may be closed at their outer ends in any suitable manner as by means of the screws 39.

15

In order to heat the sealing sheets so as to condition the thermoplastic adhesive on them, each of the sealing sheet carrying devices 23 is provided with a metal heating and pressing pad 40 which serves also to press the sheets against the tops of the cams. This pad is of somewhat greater area than the sealing sheet and its surface is arcuate in side view and substantially straight in the other direction as shown in Figs. 9 and 11. The four tubes 30 for each of sheet carrying devices 23 project through apertures 41 in pads 40 (Fig. 3). These apertures permit pads 40 to move in a radial direction during the rotation of rotary head 9 and also permit them to have a pivotal support so as to press the sealing sheets against the tops of the cans with a rolling or rocking movement. These apertures are also large enough to provide a substantial air space between the tubes and the heated pads to retard the transfer of heat to the tubes and thence to the rotary head.

20

Each of pads 40 is pivoted on a horizontally projecting rod 42 which is welded or otherwise permanently secured in a recess at the apex of a block 43 (Fig. 13) bluntly pointed in side view and flanked on either side by extensions or wings 44 and forming a support for pad 40. The pivotally mounted pads 40 are held centered with their curved surfaces concentric with the axis of shaft 26 by means of a pair of coil springs 42a. Block 43 is mounted on body 22 of rotary head 9 by means of a rod 45 fixed to and projecting radially inward from the center of block 43. Rod 45 is received with a sliding fit in a bushing 46 mounted in a radial opening in one of the enlargements 29. The inner end of this opening is vented at 47 to permit rod 45 to slide freely in bushing 46.

25

Each of the blocks 43 is provided with a cam follower roller 48 suitably mounted on a pin 49 which projects from the inner face of block 43 to position roller 48 within the slot 50 of cam member 24. This cam member is firmly secured to frame 15 by means of screws 51. Block 43 with its wing portions 44 is maintained in contact with the flat annular face of cam member 24 by the support of rods 45 in bushings 46 and in this way the supporting rod 42 for the pad 40 is held in parallel relation to the axis of the rotary head 9.

30

Each of the pads 40 has an inwardly extending boss which is apertured to receive an electric

25

heater 52. In order to supply current to these four heating devices their respective connecting wires 53 are electrically connected to two concentric slip rings 54 which are embedded in an annular insulating ring 55. These parts are secured by means of suitable screws 56 and spacer blocks 57 to the enlargements 29 of body member 22 of rotary head 9, and slip rings 54 consequently rotate with this head.

Current is supplied to slip rings 54 by means of a pair of stationary brushes 58 (Figs. 9 and 3). These brushes are mounted in yielding contact with the surface of rings 54 in a well understood manner. Brushes 58 form a part of a connection box 59 to which the supply conductors are connected through a cable 60. A control box 61, including a suitable cut-off switch is arranged adjacent connection box 59 and connected in the circuit of brushes 58. Connection box 59 and control box 61 are supported on an L-shaped bracket 62 (Fig. 5) which is attached to the right side of frame 15. An annular guard ring 63 of insulating material is mounted in stationary position to protect against accidental contact with the slip rings 54.

Referring now to the rotary carrier 14 and web cut-off mechanism 13, carrier 14 is a circular plate-like member (Figs. 4, 7 and 12) having two parallel arms 64 arranged 180 degrees apart and each arm having at its outer end an arcuate sealing sheet supporting surface 65. Supporting surfaces 65 have a plurality of openings 66 which communicate with passages 67 in arms 64 that extend to the rear surface of carrier 14. This is a finished surface and like rotary head 9 is maintained in contact with the surface of a stationary member 68 which is chambered to supply suction and pressure successively to the passages 67 during the rotation of carrier 14. Member 68 is yieldably mounted on frame 15 in the same way as member 36 for rotary head 9. For this purpose member 68 has an arcuate suction groove 69 (Fig. 7) to which a suction pipe 70 is connected, and a circular pressure opening 71 to which a pressure pipe 72 is connected.

Carrier 14 is fixed to the front end of a horizontal shaft 73 (Figs. 4 and 12) rotating in a bearing in frame 15. Shaft 73 is driven by means of a gear 74 fixed to its rear end (Fig. 4) and driven by an intermeshing gear 75 (Fig. 7) on a cam shaft 76 that actuates the cutting mechanism 13. Gear 75 in turn is driven by a gear 77 on a stub shaft 78 (Fig. 4), which is driven by a gear 79 of the same diameter as gear 77 and which meshes with the previously mentioned gear 27 on shaft 26 of the rotary head 9.

Considering now the mechanism for severing web 10 into the individual sealing sheets, the web which travels toward the right at the bottom of magazine roll 11 first passes over a de-curling bar 80. Thence, the web passes between the power driven feed roll 12 and cooperating pressure roller 81 by which it is continuously fed toward the left along an open trough or channel 82 by which it is guided to the severing mechanism 13. De-curling bar 80 is a square or rectangular member having sharp corners and provided with a round supporting shank 83 (Fig. 3) which is received in an aperture in a boss projecting out from frame 15.

A clamping screw 84 engages the shank and facilitates the adjustment of the bar so as to cause web 10 to be drawn around one or more of its corners. A weighted lever 85 rests on magazine roll 11 in order that the web may be

drawn over the curling bar under suitable tension. Pressure roller 81 is carried on an arm 86 which is pivoted at its right end on a part of frame 15. Arm 86 is biased upwardly by means of a coil spring 87 to cause roller 81 to be held against the web with the desired pressure. The trough 82 is supported on a bracket 88 (Fig. 8) which is in turn secured to another boss projecting from frame 15.

Feed roll 12 is fixed to the forward end of a horizontal shaft 89 suitably journaled in frame 15 and having a sprocket 90 (Fig. 3) at its rear end which is driven by a chain 91 from a similar sprocket vertically below sprocket 90 and mounted on shaft 26 for rotary head 9, which as previously described is gear driven from short shaft 18 and vertical shaft 16.

The left end of open trough 82 is curved downwardly close to the path of rotation of the two sheet supporting surfaces 65 on arms 64 of the vacuum rotary carrier 14 as shown in Figs. 7 and 8; and delivers the end portion of the web 10 to severing mechanism 13 which includes a knife 92 and an anvil 93 (Fig. 7), and also onto one of the two supporting surfaces 65, these parts operating in timed relation as is about to be described. In order to allow the web to move into contact with surface 65 the central part of the end portion of channel 82 is cut away as indicated at 94 in Fig. 6.

A curved blade 95 guides the web downwardly against a supporting surface 65 as it moves toward the cutting position so that the web will be within the range of the vacuum applied through the openings 66. The end of the blade is at the line of cutting and frees the end of the strip from the knife 92 as it recedes. Blade 95 is attached by screws 96 to a support 97 which is pivotally mounted at 98 at the end of a boss 99 extending from frame casting 15. Boss 99 is adjacent another boss 100 at the end of which is mounted a stop block 101 against which a stop screw 102, adjustably mounted on plate support 97, operates. In this way blade 95 acts yieldingly against the outer surface of web 10, being biased downward by its weight, and being limited in its downward movement by the stop screw 102 which prevents blade 95 from becoming a drag on the web to resist its advancement by feed roll 12.

The mechanism for operating knife 92 and anvil 93 of severing mechanism 13 is shown in enlarged side view in Fig. 7, and also in Figs. 4 and 5. Knife blade 92 is mounted at the end of a curved arm 103 which is fixed to the front end of a rock shaft 104, and anvil 93 is mounted on the upper end of a straight arm 105 fixed to the front end of a second rock shaft 106. Rock shafts 104 and 106 extend through to the rear of frame 15 in which they are suitably supported in bearings. These two shafts and their respective severing devices are actuated by means of two cams which are keyed to the rear end of cam shaft 76, the knife operating cam being indicated at 107 and the anvil cam at 108. Rock shaft 104 which operates knife 92 is actuated by a cam follower roller 109 which is pivoted on the end of an arm 110 keyed to the rear end of shaft 104, while rock shaft 106 for the anvil 93 is actuated by a cam follower roller 111 which is pivoted at the end of a curved arm 112 keyed to the rear end of shaft 106.

Knife 92 and anvil 93 are shown in open position in Figs. 1 and 7 and in closed or cutting position in Fig. 8 which shows the parts an instant after the severing of the sealing strip 51. From Fig. 5 it will be seen that anvil 93 extends

inwardly from arm 105 into the path of rotation of the two arms 64, each with its sealing sheet supporting surface 65. From the shape of cam 108 (Fig. 7) it will be understood that anvil 93 is moved into the cutting position which has been indicated by the radial line 113 quickly after the passage of each of the arms 64, cam shaft 16 being rotated at twice the speed of carrier shaft 13. That is to say, arm 105 moves anvil 93 outward from the position of Fig. 7 and to a position close to the path of arms 64 as one of these arms approaches the cutting line 113, and immediately after the arm passes this line anvil 93 abruptly shifts outward to the cutting position. At the same instant, cam 107 rocks shaft 104 and causes knife 92 to sever the strip as shown in Fig. 8 by a quick in and out movement. Anvil 93 gradually moves back to its inward position to allow the next arm 64 of rotary carrier 14 to move past the anvil and toward the cutting line 113.

Knife 92 is yieldably held against a flat surface 114 on the end of arm 103 by means of a coil spring 115 on a small bolt 116 which is anchored in the head of arm 103 and passes loosely through an aperture in blade 92. This permits blade 92 to have a sloping edge so as to sever the web with a shearing cut. During the instant that the blade and anvil are severing the web, the web, which is fed continuously forward by feed roll 12, is permitted to bow or loop as indicated at 117 between two stationary rods or wires 118 which are adjustably positioned on channel 82 for this purpose. The cutting action being rapid, the bow formed is small and immediately straightens out when the knife 92 recedes.

The operation of the apparatus is as follows:

All of the parts of the machine operate continuously, there being no intermittent operation other than the oscillating motion of the arms 103 and 105 of the severing mechanism which is also continuous as just described. The surface or rotative speed of the ends of the sealing sheet supporting tubes 30 of the rotary head 9 is arranged to be the same as that of the sheet supporting surfaces 65 of carrier 14 and also the same as the linear speed of the tops of the salt cans C₁—C₄ on table 4. The speed of feed roll 12 is arranged to feed the desired length of sealing strip to the cutting position 113 as each of the arms 64 of carrier 14 reaches this position. The speed of feed roll 12 therefore depends upon the length of the sealing sheet desired. This can be changed by substituting different size sprockets on shafts 89 and 26 (Fig. 3).

As each of the sheet supporting surfaces 65 of the two arms 64 of carrier 14 reaches the cutting position 113 (Fig. 7) the end of web 10 which has been fed forward by feed roll 12 beyond the end of trough 82 is picked up and supported by surface 65, the vacuum applied through passages 66 causing the end of the strip to be drawn toward and to adhere to this surface. Since the speed of surface 65 is greater than that of the web, one will slip on the other. As soon as surface 65 has passed severing position 113, the knife 92 and anvil 93 operate cutting off the extended end of the web and forming a sealing strip such as shown for example at S1.

This sealing strip immediately assumes the higher speed of surface 65 and is carried downwardly in a counterclockwise direction to a position diametrically opposite the cutting position 113, which may be referred to as the transfer position, where the sealing strip is transferred from surface 65 to the outer ends of tubes 30 of

one of the sheet carrying devices 23 of rotary head 9. Vacuum has been applied to these tubes at this position and the vacuum through passages 66 has been cut off and pressure applied instead so as to blow the sealing strip free of surface 65. Sealing strip S₂ is in this position and the coated side of this strip is on the outside.

In this transfer position, the heating and impressing pad 40 has been withdrawn from the end of tubes 30 as shown in Fig. 7 by the action of cam groove 50 (see Figs. 9 and 10). As the rotary head 9 continues its rotation the sealing strip is carried around in the clockwise direction through the positions S₃ and S₄, where the strip is applied to the salt can C₃. The contour of cam groove 50 is such that pad 40 is moved outwardly into contact with, or closely adjacent to the surface of the sealing sheet by the time the sheet reaches the top position shown in Fig. 9. Pad 40 remains in this position until the sealing sheet is close to the point of application to the can, then the contour of the cam changes abruptly so as to force pad 40 outwardly and press the sealing strip against the top of the can. During the next 90 degrees of travel, pad 40 is again returned to the initial position shown at the left of Fig. 9.

During somewhat more than 180 degrees of travel of rotary head 9, pad 40 is applying heat to the sealing sheet, so that by the time the sheet is pressed into contact with the can, the thermoplastic adhesive on its outer surface has been conditioned or rendered tacky so that it will adhere to the surface of the can around the margins of the sealing spout 7 and cause a proper sealing of this member.

The invention has been described in connection with one particular embodiment but it will be understood that changes may be made in the construction and arrangement of the various parts without departing from the scope of the invention which is set forth in the appended claims. Also, it will be understood that the apparatus can be used to apply sheets other than sealing strips for containers and the word container as used in the appended claims is intended to include articles with or without pouring spouts.

I claim:

1. In a device of the character described, in combination, a substantially horizontal conveyer for conveying a succession of containers, a rotary head rotatable about a substantially horizontal axis disposed above said conveyer, said head having a plurality of sheet supporting devices traveling in a generally circular path to engage the successive containers on said conveyer, a carrier rotatable about a substantially horizontal axis and a plurality of sheet supporting surfaces disposed to engage the sheet carrying devices of said rotary head, means for feeding a continuous web onto the successive supporting surfaces of said carrier, severing mechanism for successively cutting sheets from said web constructed, disposed and timed to deposit individual sheets on said carrier supporting surfaces, means for releasably holding said individual sheets on said carrier, means operated by the rotation of said carrier for moving said sheets away from said carrier and onto the respective sheet supporting devices of said rotary head, and means operated by the rotation of said head for moving said individual sheets away from said head and onto successive containers on said conveyer when

each container is brought into contact with such sheet.

2. A device of the character described as claimed in claim 1, wherein each of the sheet supporting devices of the rotary head is provided with a heated member having a pressing surface, said member being mounted to move outward and inward on said head, and a cam being arranged to cause said members successively to move into contact with the individual sheets to condition the adhesive thereon and thereafter to press the sheets onto the successive containers.

3. In apparatus of the class described, a rotary head provided with one or more vacuum supports, each for supporting a sheet, and each having a heating and pressing pad mounted on the rotary head and constructed and arranged to move outwardly and inwardly of said head, and mechanism for moving said pad outwardly into engagement with the sheet on such support simultaneously to heat the sheet and strip it from its said support and press it into adhering contact with a container, said mechanism thereafter returning said head inwardly.

4. In apparatus of the class described, a rotary vacuum head comprising a body member having one or more sheet carrying and applying devices each of which comprises a group of open ended tubes fixed to and projecting radially from said body member to form sheet supporting surfaces at their open ends, means for connecting said tubes with a vacuum source, a heating and pressing pad mounted in radially movable position on said body and provided with apertures to allow said tubes to project through the pad, and a cam and follower mechanism for causing said pad to move adjacent a sheet supported on the tubes to heat the sheet and thereafter to move it off the tubes and apply it to a container.

5. In a device of the character described, in combination, a substantially horizontal conveyer for conveying a succession of containers, a rotary head rotatable about a substantially horizontal axis disposed above said conveyer, said head having sheet carrying means traveling in a generally circular path to engage the successive containers on said conveyer, a carrier rotatable about a substantially horizontal axis and having sheet supporting means disposed to rotate adjacent said rotary head to engage the sheet carrying means thereof, means for feeding a continuous web onto the supporting means of said carrier, said web having a thermoplastic adhesive coating, severing mechanism for successively cutting sheets from said web constructed, disposed and timed to deposit individual sheets on said carrier sheet supporting means, means for releasably holding said individual sheets on said carrier, means operated by the rotation of said carrier for moving said sheets away from said carrier and onto the sheet supporting means of said rotary head, a heated

member having a pressing surface and mounted to move outward and inward of the rotary head, and mechanism for causing said heated member to move outward into contact with an individual sheet on the sheet supporting means to condition the adhesive on said sheet and subsequently to move such sheet off of its supporting means and onto a container on said conveyer.

6. In apparatus of the class described, a rotary carrier having one or more suction portions moving in a circular path, severing mechanism including co-acting cutting members constructed and arranged to move into and out of cutting engagement with each other at a cutting position, said cutting position being disposed substantially within the path of said suction portions, feeding mechanism for feeding a web at substantially uniform speed to said severing mechanism, the web thereby being severed into successive sheets of uniform length, and means for operating said severing mechanism and said rotary carrier in timed relation to one another to cause said cutting mechanism to clear each carrier suction portion and said suction portion to remove said successively severed sheets from said cutting position.

7. An apparatus as set forth in claim 6 in which the cutting members move into cutting position close behind a suction portion of the rotary carrier each time a suction portion passes through the cutting position.

8. Apparatus as set forth in claim 6 wherein the severing mechanism includes two movable cutting members, said members moving into and out of the circular path of the carrier suction portions from opposite sides of said path, said members when substantially in said path co-acting to sever the web.

9. Apparatus as set forth in claim 6 in which the rotary carrier comprises a disc-like member and each suction portion thereof is constituted of a projection from the face of such disc-like member.

10. Apparatus as set forth in claim 6 in which the speed of the web feeding mechanism can be changed in order to vary the length of the severed sheets.
